JAMES S. ATTERBURY AND THOMAS B. ATTERBURY, OF PITTSBURG,
PENNSYLVANIA.

Design No. 4,457, dated November 8, 1870.

DESIGN FOR THE ORNAMENTATION OF GLASSWARE.

The Schedule referred to in these Letters Patent and making part of the same.

To all whom it may concern:

Be it known that we, JAMES S. ATTERBURY, and THOMAS B. ATTERBURY, of Pittsburg, in the county of Allegheny and State of Pennsylvania, have invented and produced a new and original Design for the Ornamentation of Glassware, of which the following is a specification, reference being had to the accompanying drawing, in which—

Figure 1, plate 1, is a side view of a glass pitcher, made in accordance with my design.

Figure 2, plate 1, is a top view of the same.

Figures 3 and 4, plate 2, are perspective views of a glass dish and its cover, made in accordance with my design.

The nature of my design consists in the flutes α , forming the body of the article terminating in a fluted or scalloped edge, α' . The contour of the article or articles approach the form of a melon, which, with

the flutes surrounding the same, gives to it the appearance of a melon having one end cut off in a scalloped form.

The drawing represents two different kinds of articles of glassware, viz., a cream pitcher and a covered dish; but we contemplate ornamenting other kinds, whole sets, of vessels of glassware, with the melon design shown in the drawing.

Therefore we do not claim any special-shaped vessel; but

What we do claim is—

The within-described melon design for the ornamentation of glassware, as shown.

JAMES S. ATTERBURY.
THOS. B. ATTERBURY.
